CLAIM

The ornamental design for tool handle, as shown and described.

DESCRIPTION

FIG. 1 is a perspective view of a tool handle showing my new design;

FIG. 2 is a front view thereof; the opposite side being a mirror image of the shown.

FIG. 3 is a left view thereof;

FIG. 4 is a right view thereof;

FIG. 5 is a top view thereof;

FIG. 6 is a bottom view thereof; and,

FIG. 7 is the perspective view embodying the utilization of tool handle in which the broken line is for illustrative purposes only and forms no part of the claimed design.
